(57) CLAIM

The ornamental design for a spa as shown and described.

DESCRIPTION

FIG. 1 is a front, top, and left side perspective view of a first embodiment of a spa.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, top, and right side perspective view thereof.

FIG. 9 is a front, top, and left side perspective view of a second embodiment of a spa.

FIG. 10 is a front view thereof.

FIG. 11 is a rear view thereof.

FIG. 12 is a left side view thereof.

FIG. 13 is a right side view thereof.

FIG. 14 is a top view thereof.

FIG. 15 is a bottom view thereof.

FIG. 16 is a rear, top, and right side perspective view thereof.

FIG. 17 is a front, top, and left side perspective view of a third embodiment of a spa.

FIG. 18 is a front view thereof.

FIG. 19 is a rear view thereof.

FIG. 20 is a left side view thereof.

FIG. 21 is a right side view thereof.

FIG. 22 is a top view thereof.

FIG. 23 is a bottom view thereof; and,

FIG. 24 is a rear, top, and right side perspective view thereof.

Broken lines are used to illustrate features of the spa which form no part of the claimed design.

1 Claim, 18 Drawing Sheets
